UNITED STATES PATENT OFFICE.

ORVILLE C. MANN, OF OAK PARK, ILLINOIS.

SPREADER.

1,295,551.

Specification of Letters Patent. Patented Feb. 25, 1919.

Application filed February 4, 1918. Serial No. 215,393.

To all whom it may concern:

Be it known that I, ORVILLE C. MANN, a citizen of the United States, residing at Oak Park, in the county of Cook and State 5 of Illinois, have invented certain new and useful Improvements in Spreaders, of which the following is a specification, reference being had to the accompanying drawings, forming a part thereof.

10 The purpose of this invention is to provide an improved apparatus to be mounted on a car for operating upon the road bed of a railway track for spreading ballast and the like and auxiliary purposes. It consists 15 in the elements and features of construction shown and described, as indicated in the claims.

In the drawing:

Figure 1 is a side elevation of a car 20 equipped with a structure embodying this invention.

Fig. 2 is a plan view showing a spreader wing at one side only of the car.

Fig. 3 is a plan view showing a spreader 25 wing at both sides of the car with certain special appurtenances added thereto.

Fig. 4 is a front elevation of the ditching device.

Fig. 5 is an end view of the same.

30 Fig. 6 is a detail plan view of a part of the car showing one wing with a modified ditching device.

Fig. 7 is a detail side elevation having the spreader wing collapsed against the side of 35 the car.

Fig. 8 is a detail section at the line, 8—8, on Fig. 7, on an enlarged scale.

Fig. 9 is an enlarged section at the line, 9—9, on Fig. 8.

40 Fig. 10 is a section at the line, 10—10, on Fig. 8.

Fig. 11 is a section at the line, 11—11, on Fig. 7.

45 Fig. 12 is a section at the line, 12—12, on Fig. 11 on an enlarged scale.

Fig. 13 is a detail section at the line, 13—13, on Fig. 2 on an enlarged scale.

Fig. 14 is a section at the line, 14—14, on Fig. 13.

50 Fig. 15 is a section at the line, 15—15, on Fig. 3.

Fig. 16 is a section at the line, 16—16, on Fig. 15.

Fig. 17 is a section at the line, 17—17, on Fig. 3 on an enlarged scale.

In the structure shown in the drawings 1

is one of the side sills of the car; 2 is one of the center sills; 3 is a portion of one of the end sills or main transverse members of the base frame of the car. For the purpose 60 of this invention there is mounted upon the outer side of each of the side sills, 1,—only one of them being shown in the drawings,—a standard or bracket, A, for supporting a hinge fitting by which the spreader member 65 at that side is to be hinged for swinging so as to project obliquely in either direction for gathering or spreading according to the direction in which the car is moving. In order to properly brace the car base frame, 70 it is constructed with cross sills, 4, 4, 4, at suitable positions in the length of the car, not only for properly stiffening the car for its general service, but specifically for taking the stress transmitted transversely from the 75 spreading and ditching devices; and for this specific purpose there are such transverse sills proximate to the position of the hinge-carrying bracket proximate to the position of the spreader brace footings, as hereinafter more 80 particularly described. To this standard or bracket, A, there is hinged the main spreader member, B, adapted to be swung as above mentioned, so as to extend obliquely off from the car toward either end thereof. For 85 bracing this spreader member or wing, B, at either of said positions,—that is, extending obliquely toward either end of the car,—there are provided upon the main sill, 1, mounted for sliding and securement at a 90 plurality of working positions upon the outer side thereof, bracket plates or hangers, C, C, for mounting brace footings formed by staples, C¹, C², two on each of said hangers, one above the other; and there are provided 95 for extending between the brace footings of either of said hangers and the outer end portion of the spreader wing, B, compression brace members, D, provided at their 100 opposite ends with fittings for pivotally connecting the brace member at one end with the spreader wing, B, and at the other end with said brace footing. In order that the spreader wing may be thus braced in either of its two positions mentioned, it is provided upon its opposite sides near the outer end, with stapled fittings, C¹, which are herein- 105 after more particularly described, adapted for pivotal connection thereto of the compression brace members.

In addition to the main spreader wing, B, there is provided an under-car spreader

wing, E, which is made fast to the hinge member, B¹, hereinafter described, at the inner end of the outer or main wing, B, and which is constructed in such a manner as to 5 extend past the supporting bracket or standard, A, under the car to a point substantially above the nearer track rail. The under car spreader wing is sustained in proper position for doing its work and overcoming 10 the resistance of the material to be spread, by means of tension members consisting preferably of chains, J, J, each including a turn-buckle, J¹, and clevises, J², J², one at each end, for engagement respectively with 15 eyes, E⁵, on the inner end of the wing, E, and eyes, J³, on the inner side of the sill, 1. It will be understood that the eyes, J³, are duplicated at equal distances in opposite directions from the bracket or standard, A, for 20 securing the tension member in either of the two positions of service of the under-car spreader wing, E.

For the reason, however, that obviously, 25 it is not practicable to have this under-car spreader wing swing under the car from the one position to the other while the main wing swings outside the car between its two positions, said under-car spreader wing is arranged to be detachable from the outer 30 or main spreader wing, being also reversible vertically so that it may be operated either edge up, and the main spreader wing being constructed for attaching said under-car spreader wing at either side or surface according to the position of the main spreader wing, this attachment being in each position to the outer side of said main spreader wing.

The detail construction of the mounting 40 and hinge connections of the spreader wing will now be described. The bracket or standard, A, comprises a base web, A¹, having its greatest width at an intermediate portion of its length at which it laps on the 45 outer side of the side sill, being cut away equally at opposite edges to narrow it below the lower edge of said sill, and being tapered narrowing from the upper edge of the sill to a similarly reduced width at the upper 50 end. By means of parallel longitudinal ribs, A², A², projecting from the web, A¹, and having inwardly-turned flanges, A³. There is formed a vertical parallel-sided channel with a slot in its outer wall, said slot being 55 the interval between the two flanges, A³. This channel receives the hinge member, A⁴, which is adapted to be inserted longitudinally in said channel, and to be secured at proper height by a key, A⁵, and stopped 60 at lowered position by a flange, a⁶, at the upper end of the member, A⁴, colliding with lugs, a⁵, a⁵, which project at opposite sides of the channel in the standard, A¹. It will be understood that the member, A⁴, is introduced at the top of the standard before 65

the stop plate, 18, is applied and secured to the top of the standard. The main spreader wing, B, is formed with two metal plates, b¹, b¹, spaced apart as seen in Figs. 10, 11 and 15, and having the interval between them filled with planking, b², said plates having their lower edges flexed inward toward each other, and meeting, as seen in Fig. 11, and lapping upon each other for a distance approximately equal to the 75 distance between the plates and riveted together at their lapping marginal portions, as seen in Fig. 11.

The hinge member, B¹, counterpart of the member, A⁴, is constructed for pivotally adjustable connection with the main spreader wing, B, to permit said wing to swing vertically edgewise through a limited angle in moving to and from its working position; and for that purpose a tongue plate, B⁴, is 80 secured rigidly between the plates, b¹, b¹, of the spreader wing at the inner end of the latter, and said tongue plate engages in a channel formed in the outer edge of the hinge member, B¹, from top to bottom thereof. The tongue plate is secured in said channel by a pivot bolt, b⁴, at about the middle of the vertical extent of said tongue plate and channel, and bolts, b⁵, b⁵, are inserted through the parts at positions equally 85 distant above and below the pivot bolt, b⁴, the tongue plate having curved slots, b⁶, for said bolts to permit angular movement of the wing about the pivot bolt, b⁴, in the lifting and lowering movement. The two hinge 90 members, A⁴ and B¹, are connected by a pintle, a⁶.

The under-car spreading wing consists of a metal plate, E, reinforced on its inner side by horizontally extending angle-iron 105 members, E¹, E¹. Said metal plate laps on the outer side of the main spreader wing, B, and is secured to said main spreader wing by bolts e¹, which take through the hinge member, B¹. The plate, E, constituting the under-car spreader wing is notched at the inner end at both the upper and the lower corner, as seen at e, Fig. 13, in order to overhang the track rail which is accommodated by the notch. This plate is made substantially symmetrical about a medial longitudinal line, both as to the notches above mentioned and as to the bolt holes by which it is secured to the hinge member, B¹, of the main spreader wing, so that said plate can 110 be applied to said spreader wing at either side of the latter, being inverted for shifting it from one side to the other, as is necessary in order that either side may extend past the hinge-supporting standard or 115 bracket, A, and have the reinforcing angle iron at the inner side when in operating position.

A stay cable, B³, is provided, connected by a turn-buckle, b³, to the upper end of 120

125

the hinge member, A⁴, and at the lower end to an eye, B³⁰, secured to the wing, B, near the outer end of the latter. This stay cable serves to relieve the hinge of the severe cramping which the weight of the wing would otherwise impose upon it. The opposite ends of the compression brace member, D, are provided with fittings, D², each comprising an eye, d², for engaging the staple members, c³, anchored in fittings, C¹, on the main spreader wing and on the outer side of the side sill, 1, as above mentioned, said fittings being identically formed, the means for anchoring said staples being that said fittings, c¹, being provided with apertures for the staple legs have also each a rectangular cross aperture, c⁴, spanning the interval between the two staple leg apertures and cutting into each of them, and the staple legs are provided with notches, c⁵, c⁶, facing each other in position to register with said rectangular cross aperture when the staple is properly inserted in the fitting, and a rectangular metal key, C⁶, is provided, adapted to be driven into said cross aperture and engage said notches of the staple legs; and so retain the staple legs in the fitting. For disengaging the compression brace member from either of its end connections, the key, C⁶, being knocked out, the staple legs can be withdrawn from the plate, C¹, and the staple being disengaged from the eye on the end of the brace member, may be re-inserted in the fitting and secured by the key if desired, to prevent loss of either staple or the key.

The brackets, C, are supported for sliding and securement at a plurality of working positions on the side sill by means of slide bearings H, made of two angle iron bars secured with a flange of each back to back to form a longitudinal horizontal rib, H¹, (see Fig. 17) their other flanges being bolted to the side sill but spaced off therefrom a short distance by spacing blocks, h, at the ends of said slide bar, H, where the securing bolts take through said flanges and spacing blocks into the sill. The brackets, or hangers, C, are formed to embrace the rib, H¹, and the upper and lower edges of the flanges, H², for sliding along said bar, H; and to secure the bracket at any one of a plurality of desirable working positions, the rib, H¹, has notches, h¹, at suitable intervals along the length of the slide bar, which may be engaged by a key, K, inserted through the rib, C¹⁰, of the bracket, C, which embraces the rib, H¹, of the bar, H.

For operating the spreader wing to lift it out of operating position or allow it to move outward and downward to a desired position for working, there is provided a cable connection at 12, on the inner side of the wing, B, near the heel or inner end and near the lower edge; and there is mounted on the car

at a position substantially as far from the hinge pivot of the wing as said cable connection, a pulley block, 13, pivoted for swinging about an axis longitudinally of the car to permit the pulley, 16, thereon to swing 70 to accommodate the draft of the cable, 17, running from it to the wing, B; and at a point some distance along the car from said pulley hanger, 13, there is mounted on the side of the car a pulley, 15, about which the 75 cable turns upward to extend over a pulley on the end of a derrick, jib arm or boom indicated at T which is supported and operated on the car by means not illustrated.

When the wing is to be lifted and swung 80 in toward the car out of its operating position, the pins, A⁵, are withdrawn from the hinge member, A⁴, to free said hinge member for sliding upward in the standard, A, and the key, K, is withdrawn to free the 85 bracket, C, sliding along the bar, H. The pull of the cable, 17, tends to lift the wing B, and also to swing it in toward the car and to slide the brackets, C, along the bar, H; but before any considerable inward movement has occurred the direction of pull of the cable upon the wing becomes sufficiently upward to cause upward movement of the wing to predominate, and by reason of the cable connection being so near the pivot 95 formed by the bolt, b⁴, and the consequent heavy overhang of the wing outside the cable connection, at first operates to lift the wing bodily, sliding the hinge member, A⁴, up along the standard, A, until the 100 movement is stopped by the encounter of the said hinge member, A⁴, with the stop, 18, provided for that purpose; and thereafter the pull of the cable tends to swing the wing up pivotally about the pivot-bolt, b⁴, while 105 completing the inward-swinging movement of the wing toward the car.

For holding the spreader wing safely in its in-swung and elevated position out of service, there is provided on the upper edge 110 of the wing near the outer ends a staple-like projection, P, which is adapted to enter between the ears, g, g, of a bracket, Q, which is mounted on the car side, projecting outward therefrom; and a bolt, Q¹, which is 115 removably carried by said ears and engages them both, being withdrawn to permit the staple, P, to pass between the ears, as the wing is drawn up into place alongside the car and is re-inserted, passing under the staple and through both ears, and thus secures the wing against the car or a proper position with respect thereto, the outer end being carried by the bracket, Q, and the inner end by the key, A⁵, in the standard, A. 125

When the wing, B, is operating as a spreader wing, being for that purpose adjusted diverging from the car rearwardly with respect to the direction of advance of the car, it is often desirable, especially when 130

spreading ballast, to prevent the material from being spread so widely as the entire reach of the spreader wing, and on the contrary to retain the ballast within a certain limited distance from the track rails. For this purpose the spreading wing, B, has provisions for hinging to it at either side which may be the forward side when it is operating as a spreader as above stated, a ballast-retaining or spread-limiting wing, L, which is held at a position substantially parallel with the car and track, by a tension rod or cable, L¹, extending from the outer end of said ballast-retaining wing, forward in the direction of advance of the car to any available point of attachment for draft, and preferably to a car ahead. When such ballast-retaining member is connected to a car ahead, as indicated, such connection serves an important purpose in addition to merely holding the ballast-retaining member in place, which may be understood upon considering that the resistance of the material engaged by the spreader operates ordinarily to force the car transversely of the track away from the side at which the spreader is operated; but when the spreader is connected by means of the ballast-retaining wing and the cable therefrom to a car ahead of that upon which the spreader is carried, the rigid triangle consisting of the side of the car, the spreader wing, B, and the brace, D, operates as a rigid lever arm of the car whose operative length for the purpose of draft by the car ahead is the distance of the hinge of the ballast-retaining wing to the wing, B, off from the vertical plane of the nearer track rail; and the draft of the car ahead, operating through the connections made upon this lever arm, tends to swing the rear end of the car about a pivot consisting of the forward truck connection of the car, thus tending to pull at the rear portion of the car toward the side at which the spreader is operating, and to a very appreciable extent counteracting the tendency of the resistance of the ballast to push the car in the opposite direction, as above noted. It will be observed that this result may be attained by any connection of the spreader wing at a point well removed from its hinge at the side of the car out toward its outer end, for draft upon the spreader exerted by the car ahead. That is to say, for this purpose the thrust-retaining wing, L, may be regarded only as one link in the draft connection from the car ahead to the spreader wing, operating as such connection independently of its function as ballast-retainer.

The spreader wing, B, may be utilized to carry a ditching or drain-cutting plate or shovel, M, at a position outside the ballasted area.

It should be noticed that the angle to the line of advance at which the spreader wing stands, and which is the desirable angle for the function of the spreader as such, is not the angle of greatest efficiency of a ditcher; and on the contrary, a blade set at that angle to the line of advance would fail to be of any effective service in ditch-cutting in any stubborn earth, on account of the extreme wedging action of the earth, tending to swerve the blade into parallelism with the direction of advance. For this reason it is necessary in mounting a ditching blade on the spreader arm to provide it with connections by which it may be set much more nearly at right angles to the line of advance than the spreader stands. This is accomplished by hinging the ditcher at its inner vertical edge to the forward side of the spreader at a line which is substantially vertical at the working position of the spreader, and holding it at the desired angle to the spreader by a draft cable, 20, connected to it near the outer edge and extending forward, preferably to the next car ahead, so as to obtain as nearly a direct forward pull as possible. The ditcher blade is desirably shaped as shown with its lower edge, m, to the shape in cross-section of the ditch to be cut, and curved forward as seen at M¹, so as to cut under or scoop the earth instead of merely scraping it. The effective working angle of the ditcher is about 25 degrees back of a position at right angles to the line of advance, while the effective working position of the spreader is nearly 45 degrees diverging outward and rearward from the line of advance; so that the angle between the ditcher and the spreader will be about 20 degrees.

The ditching shovel will frequently be used when the spreader wing is not operating for spreading but is merely used as an arm for carrying said ditching shovel at the proper distance from the track. Under these conditions the ditcher carried rigidly at the end of the spreader arm operates, by reason of the resistance which it encounters, with a tendency to force the car transversely of the track toward the side at which the ditcher is thus operating,—that is, it tends to derail the car on that side. By hinging the ditcher to the spreader arm as shown, instead of carrying it rigidly at the end of that arm, and connecting it at the outer end by draft connections to the car ahead, the draft connections operate nearly directly in the line of the resistance encountered by the ditching shovel, and it is possible to set the ditching shovel at such an angle to the line of advance that the draft will be substantially as if the shovel were set directly across this line of advance and pulled directly in that line,—that is, without any tendency to

exert a side draft or pull upon the car by which the ditcher is carried; and this is the result aimed at in the hinge construction, draft connection and angle of the ditching shovel to the line of advance which characterizes the construction shown in the drawings.

Fig. 3 shows a ditching shovel carried on a long arm hinged to the spreader at the position above indicated for hinging the shovel as at first described; the arm being of sufficient length for positioning the shovel properly to cut a ditch about twenty-five feet or more distant from the center of the track. The arm, W, is an angle bar and the shovel is secured to it at any desired position in the length thereof, a multiplicity of bolt holes being provided in the horizontal flange of the angle bar for that purpose.

20 I claim:

1. In combination with a car base structure a bracket mounted on the outer side of one longitudinal side sill; a spreader wing having a hinge for folding about a vertical axis, of which hinge one member is mounted for sliding up and down in said bracket; a compression-brace member pivotally connected at one end to the wing, and means on the car side sill for pivotally engaging the other end, said means comprising a slide-way mounted on the car; a bracket slidably mounted on said slide-way; means for disengageably securing the bracket at a predetermined position on the slide-way, and means for operating the wing comprising a cable connected to the wing at a point relatively near to the hinge, and a guide for the cable on the car, positioned for causing the pull of the cable on the wing to be upward and inward.

2. In combination with a car base structure, a bracket mounted on the side sill of the car; a spreader wing having a hinge folding about a vertical axis of which hinge one member is mounted for sliding up and down in said bracket; two compression braces, each pivotally connected at one end to the wing, one above the other, and means on the car side sill for pivotally engaging the opposite ends of said braces; said means comprising a slide-way extending longitudinally of the car side-sill; a bracket to which the braces are connected slidably mounted on said slide-way; means for releasably securing the bracket at a predetermined position on the slide-way, and means connected with the car for lifting and swinging the wing.

3. In combination with a car base structure, a bracket mounted on the side sill of the car; a spreader wing having a hinge for folding about a vertical axis of which hinge one member is mounted for sliding up and down in said bracket, the other hinge mem-

ber being jointed for swinging of the wing 65 edgewise up and down; a pair of compression braces connected at one end, one above the other, to the wing; means on the side of the car for pivotally engaging the opposite ends of said braces, said means being mounted for sliding lengthwise of the car, and means for releasably securing said slideable member at a pre-determined position in the path of sliding; a hoisting cable connected to the wing at a point relatively near to and outward from the joint in the second mentioned hinge member, and a guide for the hoisting cable positioned on the car at a point above and inward from its connection to the wing.

4. In combination with a car base structure, a bracket mounted on the outer side of one longitudinal side sill; a spreader wing hinged at one end to said bracket for swinging the other end toward either end of the car to a position oblique to said sill; a compression brace member adapted to subtend the acute angle between the wing and the side sill, the wing having at its opposite sides means for disengageably engaging one end of the brace, and the car side sill having toward the opposite ends means for alternative engagement of the other end of the brace.

5. In combination with a car base structure, comprising a longitudinal side sill, a bracket mounted upon the outer side of the side sill at substantially the middle point of the length of the car; a spreader wing hinged to said bracket for swinging alternatively toward either end of the car to a position making an oblique angle with the side sill; a bracket mounted on the side sill and adapted to be secured at a determined position thereon at distances in opposite directions from the middle bracket; a pair of compression braces and means for disengageably connecting them at one end, one above the other with the wing alternatively at opposite sides thereof; and means on the oppositely-positioned brackets for connecting the other ends of the braces.

6. In combination with a side sill, the hinged wing and the compression brace member, fittings for engaging the brace member comprising each a plate having apertures for staple legs; a staple adapted to enter said apertures, having notches facing each other on the inner side of the legs, the plate having a key aperture extending transversely of the direction of the staple leg apertures and in width spanning the interval between them and opening into them, and a key adapted to be inserted in said key aperture and to engage the notches of the staple legs.

7. In combination with a car base structure, a spreader wing hinged to the side of

the car for extending off therefrom obliquely in either direction for occupying either of two symmetrically-disposed positions with respect to the car, and an under-car spreader wing formed symmetrically about a middle longitudinal line having reinforcements on one surface disposed symmetrically with respect to said middle line, whereby it is adapted by inversion to be applied to which-
5 ever side of the main wing is outermost, and thereby to occupy symmetrically-disposed positions with respect to the two symmetrically-disposed positions of the main wing, and means for securing the under-car
10 wing to the main wing in such inverse positions at the opposite sides of the main wing respectively.

8. In combination with a car base structure, a main spreader wing hinged to the
20 side of the car for extending off therefrom obliquely in either direction to occupy two symmetrically-disposed positions with respect to the car, and an under-car spreader wing detachably secured to the main wing
25 so as to be sustained by the hinged support of the latter; means for securing said under-car wings at the outer side of the hinged pivot, and at either side of the main wing; whereby said under-car wing is adapted to
30 be shifted by detachment and re-attachment from one side to the other of the main wing when the main wing is shifted from one oblique direction to the other.

9. In a railway track spreader, a spreader
35 wing comprising two plates spaced apart for the thickness of the wing, and having each at the lower longitudinal edge an in-

wardly-offset flange, said flanges lapping each other and being riveted together to form the cutting edge of the spreader wing. 40

10. In combination with a car base structure, a spreader wing hinged thereto for swinging out laterally therefrom, and means for bracing the wing off from the car at a relatively small angle thereto; a ditching blade hinged at its inner vertical edge to the forward side of the spreader wing near the outer end thereof, and adapted to be set diverging forward from said forward side, and a draft connection from the outer 50 end of said ditcher blade extending forward for connection with a car ahead of that on which the spreader wing is mounted.

11. In combination with a car base structure, a spreader wing hinged thereto for 55 swinging out laterally therefrom, and means for bracing the wing off from the car at an angle thereto; an arm hinged at its inner end to the side of the spreader wing near the outer end of the latter, and adapted to be 60 set diverging forward from said forward side and extending for a considerable distance outward; a draft connection from said arm extending forward for connection with the car ahead of that on which the spreader 65 wing is mounted, and a ditching shovel on said arm, the arm being provided with a multiplicity of mounting and securing places for said ditching shovel along the length of the arm. 70

In testimony whereof, I have hereunto set my hand at Chicago, Illinois, this 31st day of January, 1918.

ORVILLE C. MANN.
